UNITED STATES PATENT OFFICE

HEINRICH HOPFF, OF LUDWIGSHAFEN-ON-THE-RHINE, GERMANY, ASSIGNOR TO I. G. FARBNENINDUSTRIE AKTIENGESELLSCHAFT, OF FRANKFORT-ON-THE-MAIN, GERMANY, A CORPORATION OF GERMANY

PRODUCTION OF VALUABLE ORGANIC OXYGEN COMPOUNDS

No Drawing. Application filed September 12, 1928, Serial No. 305,616, and in Germany November 5, 1927.

This invention relates to the production of valuable organic compounds.

I have found that valuable oxygen compounds can be produced from non-aromatic hydrocarbons e. g. from aliphatic or hydro-aromatic hydrocarbons, or mixtures thereof by the action thereon of carbon monoxid under pressure, in the presence of anhydrous halides of aluminium or boron or mixtures thereof, the pressure being variable within wide limits. A suitable working pressure is from about 80 to 150 atmospheres, though it will be understood that lower and any attainable higher pressures may be employed. The reaction proceeds, though slowly even in the cold and at rather low pressure such as about 50 atmospheres but it is preferable to work at an elevated temperature and at a pressure above the aforesaid pressure though, when heating, a pressure of about 10 atmospheres only can be applied.

Both individual hydrocarbons, and the cheaper mixtures of hydrocarbons, such as occur in the various petroleum fractions and are practically free from aromatic hydrocarbons, as for example petroleum ether, ligroin, lamp oil and purified petroleum jelly, also brown coal tar oils, the products of a destructive hydrogenation of substances of the nature of coal, tar, mineral oils and the like, cracking products and similar substances may be treated in this manner.

In the above reaction besides aluminium chlorid, anhydrous aluminium bromid, boron fluorid and the like may be employed.

The following examples will further illustrate the nature of the said invention which however is not limited thereto. The parts are by weight.

40 *Example 1*

A high pressure retort fitted with stirrers is charged with 100 parts of normal pentane and 100 parts of anhydrous aluminium 45 chlorid. Air is expelled from the vessel by

repeated admission of carbon monoxid under pressure, whereupon carbon monoxid is admitted under a pressure of from about 120 to 150 atmospheres, and the retort is heated to a temperature of about between 35° and 60° C., the stirrers being set in motion. Absorption of carbon monoxid begins after a short time and the pressure drops to from 50 to 60 atmospheres in the course of 5 to 6 hours. More carbon monoxid is then forced in until a pressure of 120 to 150 atmospheres is again attained, stirring being continued, and the admission of carbon monoxid is repeated until no further drop in pressure occurs. The reaction product consists of two liquid layers. The upper is composed of unaltered pentane and is removed. The dense, viscous lower layer is a double compound of aluminium chlorid and the reaction product. It is poured onto ice, acidified with hydrochloric acid and distilled in a current of steam. The major portion passes over with the steam and is contained in the distillate as an oily layer. After separating the oil from the water, shaking it with dilute caustic soda solution and separating again, it is fractionated by distillation. A considerable portion thereof boils between 114° and 116° C. and is obtained as a colorless liquid having a strong odour. The analysis of the product gives values corresponding to the formula $C_6H_{12}O$; the product is identical with ethyl isopropyl ketone. The main fraction boils between 116° and 250° C. and consists of a mixture of higher ketones which have probably been produced by condensation of the above mentioned simple ketone under the influence of the aluminium chlorid. The said higher ketones consist of colourless oils having a pleasant odour similar to that of menthol. From the caustic soda solution an oil with a rancid odour can be recovered by acidification, which oil boils between 190° and 300° C. and consists for the

main portion of a carboxylic acid corresponding to the formula $C_6H_{12}O_2$.

The pentane may be replaced by other aliphatic hydrocarbons such as butane, hexane, heptane, and the like or by mixtures of hydrocarbons such as petroleum ether, ligroin, benzine naphtha, petroleum, petroleum jelly, paraffin wax and the like. The anhydrous aluminium chlorid may be replaced by other halides of aluminium or boron such as aluminium bromid, boron fluorid and the like.

Example 2

15 A high pressure retort fitted with stirrers is charged with 100 parts of cyclo-hexane and 60 parts of anhydrous aluminium chlorid. Air is expelled from the vessel by repeated admission of carbon monoxid under pressure, followed by release of the pressure, whereupon carbon monoxid is admitted under a pressure of about 120 atmospheres and the retort is heated up to about 70° C. The reaction soon begins, the temperature rising somewhat, and the pressure drops rapidly to about 20 atmospheres. More carbon monoxid is then forced in until a pressure of 120 atmospheres is attained and the admission of carbon monoxid is repeated until no further drop in pressure occurs.

20 The reaction product consists of two layers, the upper of which is composed of unchanged cyclohexane and is separated off. The dark-brown colored lower layer is a double compound of aluminium chlorid and the reaction product. It is poured onto ice, acidified with hydrochloric acid and subjected to steam distillation. The major portion passes over with the steam and is contained in the distillate as an oily layer. After being separated from the water, the said oil is fractionated by distillation in vacuo. The reaction product distills over in an almost quantitative amount at between 100° and 150° C. at a pressure of 12 millimeters. The distillate consists of a slightly colored oil, which has an agreeable odour and an oxygen content of about 12 per cent.

25 That portion of the reaction product which is not volatilized with steam consists of a dark-colored, highly viscous oil.

30 In place of cyclohexane, other hydroaromatic hydrocarbons such as hexahydro tolue, or mixtures of hydroaromatic hydrocarbons from mineral oils, or the products of the destructive hydrogenation of substances of the nature of coal, tar, mineral oils and the like, lignite tar oils and similar substances may be employed.

Example 3

35 A mixture of 300 parts of n-butane and 300 parts of anhydrous aluminium chlorid is treated with carbon monoxid at 50° C. and about 120 atmospheres, while stirring in the

manner described in Example 1 until no further drop in pressure within the retort occurs, and the reaction product is worked up in the manner described. The oil obtained consists of about 90 per cent of ketones (boiling point 100° to 240° C.) and about 10 per cent of carboxylic acids (boiling point from 140° to 200° C.). By applying a higher temperature, for example 80° C., during the reaction, the content of the products obtained of bodies of a high boiling point is increased.

Example 4

40 500 parts of petroleum ether with a boiling point of from 35 to 50° C. are treated together with 500 parts of anhydrous aluminium chlorid with carbon monoxid at 50° C. and about 120 atmospheres, while stirring, in the manner described in Example 1, until no further absorption of carbon monoxid 45 takes place, and the reaction product is worked up in the manner described. About 300 parts of a colorless oil of agreeable smell is obtained which possesses a similar composition as the product obtained from n-pentane 50 according to Example 1.

Example 5

55 500 parts of a heavy benzine with a boiling point range from 150° to 200° C. are 60 treated with 300 parts of anhydrous aluminium chlorid and carbon monoxid, the latter being introduced under a pressure of 150 atmospheres and at 50° C., while stirring. By working up, there is obtained about 400 65 parts of a dark oil of peculiar smell which can be fractionated by distillation, the fractions of lower boiling point possessing a pleasant aromatic odour.

Example 6

70 800 parts of a petroleum fraction boiling from 150° to 300° C. which is free from olefines are stirred with 600 parts of anhydrous aluminium chlorid and carbon monoxid at 75 50° C. under a pressure of 150 atmospheres, carbon monoxid being added until a constant pressure within the reaction vessel is attained. On working up the reaction product, about 600 parts of a black oil are obtained from which 30 per cent can be obtained in the form of a pale yellow oil which is volatile with steam and has a pleasant odour. The dark constituents which are not volatile with steam are viscous and can be 80 employed as a lubricating oil.

85 What I claim is:

1. The process for the production of valuable organic oxygen compounds which comprises acting with carbon monoxid and an 90 anhydrous halide of aluminium upon a non-aromatic hydrocarbon in the liquid state at a pressure above 10 atmospheres.

2. The process for the production of valuable organic oxygen compounds which com- 95

- prises acting with carbon monoxid and an anhydrous halide of aluminium upon a mixture of non-aromatic hydrocarbons in the liquid state at a pressure above 10 atmospheres.
- 5 3. The process for the production of valuable organic oxygen compounds which comprises acting with carbon monoxid and an anhydrous halide of aluminium upon a fraction of a mineral oil in the liquid state at a pressure above 10 atmospheres.
- 10 4. The process for the production of valuable organic oxygen compounds which comprises acting with carbon monoxid and anhydrous halides of aluminium and of boron upon a non-aromatic hydrocarbon in the liquid state at a pressure above 10 atmospheres while heating.
- 15 5. The process for the production of valuable organic oxygen compounds which comprises acting with carbon monoxid and an anhydrous halide of aluminium upon a non-aromatic hydrocarbon in the liquid state at a pressure above 10 atmospheres while heating to a temperature between room temperature and about 150° C.
- 20 6. The process for the production of valuable organic oxygen compounds which comprises acting with carbon monoxid and anhydrous halide of aluminium upon a mixture of non-aromatic hydrocarbons in the liquid state at a pressure above 50 atmospheres while heating to a temperature between room temperature and about 100° C.
- 25 7. The process for the production of valuable organic oxygen compounds which comprises acting with carbon monoxid and anhydrous halides of aluminium and of boron upon a fraction of a mineral oil in the liquid state at a pressure above 50 atmospheres while heating to a temperature between room temperature and about 100° C.
- 30 8. The process for the production of valuable organic oxygen compounds which comprises acting with carbon monoxid and anhydrous aluminium chlorid upon a non-aromatic hydrocarbon in the liquid state at a pressure between 10 and 150 atmospheres while heating to a temperature between room temperature and about 150° C.
- 35 9. The process for the production of valuable organic oxygen compounds which comprises acting with carbon monoxid and anhydrous aluminium chlorid upon a mixture of non-aromatic hydrocarbons in the liquid state at a pressure between 80 and 150 atmospheres while heating to a temperature between room temperature and about 100° C.
- 40 10. The process for the production of valuable organic oxygen compounds which comprises acting with carbon monoxid and anhydrous aluminium chlorid upon a fraction of a mineral oil in the liquid state at a pressure between 80 and 150 atmospheres
- while heating to a temperature between room temperature and about 100° C.
- 45 11. The process for the production of valuable organic oxygen compounds which comprises acting with carbon monoxid and anhydrous aluminium chlorid upon petroleum ether at a pressure between 80 and 150 atmospheres while heating to a temperature between room temperature and about 60° C.
- 50 In testimony whereof I have hereunto set my hand.
